(57) **CLAIM**

The ornamental design for a tool bucket light, as shown and described.

DESCRIPTION

FIG. 1 is a perspective front view of the tool bucket light, showing my new design;

FIG. 2 is a front side view thereof;

FIG. 3 is a back side view thereof;

FIG. 4 is a right side view with the left side view being a mirror image thereof;

FIG. 5 is a top side view thereof; and,

FIG. 6 is a bottom side view thereof.

The broken line disclosure represents unclaimed portions of the tool bucket light.
